(57) **CLAIM**

The ornamental design for a sculpture with base, as shown and described.

DESCRIPTION

FIG. 1 is a top front left perspective view of a sculpture with base;

FIG. 2 is a front elevation view thereof;

FIG. 3 is a left elevation view thereof;

FIG. 4 is a rear elevation view thereof;

FIG. 5 is a right elevation view thereof;

FIG. 6 is a top elevation view thereof; and,

FIG. 7 is a bottom elevation view thereof.

The broken lines illustrate portions of the sculpture with base and form no part of the claimed design.
